(No Model.)

RAMIRO DE PALACIOS.

PISTON VALVE.

No. 307,750.

Patented Nov. 11, 1884.

UNITED STATES PATENT OFFICE.

RAMIRO DE PALACIOS, OF BERLIN, GERMANY.

PISTON-VALVE.

SPECIFICATION forming part of Letters Patent No. 307,750, dated November 11, 1884.

Application filed July 21, 1884. (No model.) Patented in England June 18, 1884, No. 9,161.

To all whom it may concern:

Be it known that I, RAMIRO DE PALACIOS, of Berlin, in the Empire of Germany, have invented a new and useful Improvement in 5 Valve-Gear for Steam and other Engines and Pumps, of which the following is a full, clear, and exact description. (I made application for Letters Patent in England, No. 9,161, dated June 18, 1884, for fourteen years.)

10 This invention relates to an improved piston-valve for steam and other engines; and it consists in a distribution-valve constructed and actuated directly by tappets on the piston-rod, as hereinafter specified.

15 I will describe the invention as applied to a steam-engine, and in order that it may be more readily understood I have illustrated it in the accompanying drawings, in which—

Figure 1 is a longitudinal section of the cylinder with a single valve. Fig. 2 is a similar view representing a cylinder with two valves arranged symmetrically, one at either side; and Fig. 3 is a top plan of Fig. 2, with the upper tappet removed. Figs. 4, 5, and 6 are enlarged sectional views of the valves.

20 The valve E in Fig. 1 is of circular section, and works like a piston within a cylindrical valve-chest, B, of the same or other length as the cylinder A, the length of the valve E being less than that of the valve-chest by the amount of its travel. The valve-chest B has a circular inlet steam-port, a, at exactly the middle of its length, and the valve E has two corresponding circular ports, d d', separated 25 by a central division-piece, e, and which ports, on the valve reaching one or other end of its stroke, respectively coincide with or come opposite to the steam-port a of the valve-chest. Both the ports d d' lead into the same longitudinal passage, b, in the valve, which terminates near each end of the valve in circular ports e e' on the side next the cylinder A, and which, on the valve reaching one or other end of its stroke, respectively coincide with corresponding ports, g g', leading into the cylinder A. Opposite to or on the same level with these ports g g' are exhaust-ports h h' in the valve-chest, at one or other of which the exhaust-steam escapes past the end of the valve 40 E when the latter is at the opposite end of its

stroke. All these ports and the faces e f f' of those portions of the valve which work over and close the ports a g g' and the faces q q' of the valve-chest may be of equal diameter or width, as in Figs. 1, 2, and 4—that is to say, 55 the diameters of ports a g g' h h' and of the ports d d' b c c', the width of the working-faces q q' and of those e f f', are all equal to one another; or, as in Fig. 5, the diameters of all the ports are equal to one another, but less than 60 the width of the working-faces q q' and e f f', which are also equal to one another; or, as in Fig. 6, the diameters of ports d d' b c c' are equal to one another, but less than the ports a g g' h h', which are also equal to one another, 65 but are less than the width of the faces q q' e f f', which are also equal to one another.

In Fig. 4 the induction and eduction ports are equal and the closure is instantaneous. In Fig. 5 the induction and eduction ports are 70 also equal, but the closure is longer and surer, and in Fig. 6 the eduction-ports are larger than the induction, the closure being nearly the same as in Fig. 5. In all cases, whatever may be the proportions, the port a must be 75 exactly at the middle of the valve-chest B and the division-piece e at the middle of the valve E. To reduce the frictional surface of the valve in its chest, the portions intermediate of its working-faces would be channeled or made of 80 reduced diameter and supplied with oil by suitable lubricators connected with orifices i i'. The valve is attached at the ends to valve-rods m m', passing through the adjacent ends of the valve-chest, and attached, respectively, 85 to cross-heads H H', whose other ends are either connected by a rod, G, passing through holes in the cylinder-covers and alongside the cylinder at the opposite side thereof, as in Fig. 1, or by another valve similar to the first and 90 symmetrical therewith, as in Figs. 2 and 3, the whole in either case forming a rigid frame capable of receiving reciprocating motion in the direction of the length of the cylinder to the extent of the travel of the valve, which, 95 as before mentioned, is equal to the difference in length between the valve and its chest. This motion is imparted to it by the piston C, having adjacent bosses F F', and a rod, D, carried through both covers of the cylinder 100

A and passing freely through holes $p p'$ in the cross-heads $H H'$, said rod having fixed upon it collars or tappets $N N'$, which, just before the piston reaches the one or other end of its stroke, respectively abut against the one or other cross-head $H H'$ and move the valve E across the cylinder-ports $g g'$, first cutting off and then reversing the induction and eduction of steam. These collars or tappets $N N'$ are fixed on the piston-rod by means of set-screws, and can be adjusted nearer to one another to vary the point in the piston-stroke at which they act on the valve, and consequently to vary the length of the piston-stroke itself, if required.

The operation is as follows: The piston C having arrived at the bottom of the cylinder A, and just previous thereto having, by means of tappet N' , moved the valve E to the bottom of the valve-chest B, steam is admitted through $a d' b c$ and g to the under side of the piston C and raises it, the valve meanwhile remaining stationary, while the exhaust-steam escapes at $g' h'$ across the valve-chest B and past the top end of the valve. Shortly before the piston C reaches the top of its stroke the tappet N on the lower end of the piston-rod D strikes the adjacent cross-head H and moves the valve E toward the upper end of the valve-chest B. In this motion of the valve its faces $f f'$ and e first pass over and close simultaneously all the ports $g g' a$ and $h h'$, which is a very important feature of the invention, after which it passes on until it reaches the upper end of the valve-chest, thus reversing the direction of the induction and eduction of steam, whereupon steam is admitted through $a d' b c'$ and g' to the upper side of the piston, the exhaust-steam then escaping at g and h across the valve-chest and past the lower end of the valve, and the same operation is repeated for the next stroke in the opposite direction. The valve E is cushioned at the end of its stroke by the exhaust-steam imprisoned between the end of the valve and the cover of the valve-chest, and which escapes with some resistance alongside the valve-rods m or m' , which pass through holes in the valve-chest covers, which are unprovided with stuffing-boxes to permit of such escape. In the case of a vertical cylinder of large size the valve-gear frame would be suitably counterbalanced, and the lower

cover of the valve-chest would have small holes for the escape of condensed water. The valve-rods $m m'$, if of round section, would be screwed into the ends of the valve E and secured by cotters s , and would be secured to the cross-heads $H H'$ by lock-nuts $n o n' o'$, and by square collars $k k'$, cottered to the rods $m m'$, and countersunk in corresponding recesses in the cross-heads to prevent them from turning, the rod G being secured to the opposite ends of the cross-heads by similar collars, $l l'$, and lock-nuts $n^2 o^2 n^3 o^3$; or the valve-rod may be of square section, in which case the collars are not required.

This improved valve-gear, which is strong, durable, and easily and cheaply constructed, can be employed, with suitable modifications in its proportions, in all situations, such as in ships, mines, vehicles, and engines generally, whether actuated by steam, compressed-air, gas, or water power.

Having now particularly described and ascertained the nature of my said invention and in what manner the same is to be performed, I declare that what I claim is

1. The cylindrical valve E, constructed with central longitudinal passage, b , inner ports, $c c'$, outer ports, $d d'$, and division-piece e , in combination with the valve-chest B, having aligned openings $g h$ and aligned openings $g' h'$, the said valve fitting said valve-chest like a piston, substantially as herein shown and described.

2. The cylindrical valve E, constructed with central longitudinal passage, b , inner ports, $c c'$, outer ports, $d d'$, and division-piece e , in combination with the valve-chest B, having aligned openings $g h$ and aligned openings $g' h'$, and with the cylinder A, piston C, piston-rod D, having adjustable tappets $N N'$ at opposite ends of the cylinder, and with the rods $m m'$ and cross-pieces $H H'$, substantially as herein shown and described.

The foregoing specification of my improved valve-gear for steam and other engines and pumps signed by me this 21st day of June, 1884.

RAMIRO DE PALACIOS.
